UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed April 6, 1922. Serial No. 549,971.

This invention relates to internal combustion engines and particularly to the means for lubricating such engines.

One of the objects of the present invention is to provide a novel lubrication system for an internal combustion engine.

Another object of the invention is to provide an internal combustion engine with an oil pump supported in its upper half and 10 extending into the lower part of the crank case to withdraw the lubricant from a low point in the crank case.

Another object of the invention is to mount all of the pump parts and accessories 15 in the upper half of the crank case while at the same time making the screen inlet of the pump accessible through the bottom of the lower half of the crank case.

Another object of the invention is to provide, in a crank case having a full screen 20 across it, a pump mounted in the upper part of the crank case and extending through the screen so that the pump inlet is accessible through the lower wall of the crank case.

25 Other objects of the invention will appear from the following description taken in connection with the drawings, which form a part of this specification, and in which:

Fig. 1 is a transverse vertical section 30 through an engine embodying the invention;

Fig. 2 is a longitudinal vertical section through the engine shown in Fig. 1, the section parts being substantially on the line 2—2 of Fig. 1; and

35 Fig. 3 is a horizontal section on the line 3—3 of Fig. 2.

Referring to the drawings 10 represents the upper part and 11 the lower part of an engine crank case, these parts being detachably secured together by a series of bolts 12. In the upper part of the crank case the crank shaft 13 is mounted in bearings 14. Some of the connecting rods 15 of the engine are illustrated in Figs. 1 and 2.

45 A cam shaft 16 is also supported in bearings in the upper part of the crank case, one of these bearings being shown at 17 in Fig. 2. The cam shaft is, of course, driven through suitable gearing or chains from the 50 crank shaft, in any desirable manner.

The lower part of the crank case has a screen 18 mounted in it some distance above the bottom of the crank case and extending substantially across the crank case so that 55 it will catch practically all of the oil which

falls from the various bearings in the upper part of the case. This screen 18 is mounted in the lower part of the crank case upon cross baffles 19 which in turn are supported on bosses 20 in the lower part of the crank case, being secured thereto by a series of screws 21. The baffles 19 are adapted to prevent too much surging of the oil in the crank case when the engine is used in an automobile or other moving vehicle. 65

The lower part of the crank case is formed with a drain opening 22 and a plug 23 is provided for the opening. There is also an opening 24 in the bottom wall of the lower part of the crank case which opening is for 70 the removal of the oil screen which is about to be described. In line with the opening 24 and of about the same size, is an opening 25 formed in the large screen 18.

For the purpose of circulating lubricating 75 oil through the various bearings of the motor an oil pump 26 is provided. This pump is shown as being of the gear type driven by a shaft 27 which extends upwardly alongside of the cam shaft 16. A worm gear 28 80 at the upper end of this shaft meshes with a worm gear 29 on the cam shaft so that the cam shaft drives the oil pump. A bearing 30 is provided in the upper part of the crank case for the gear 28 and the upper end 85 of the shaft 27.

The oil pump 26 is detachably secured to the upper part 10 of the crank case, the pump casting having ears 31 through which bolts 32 are passed to thus secure the pump 90 in place. The gears of the pump are shown at 33 in both Figures 1 and 2.

The outlet from the pump casing is shown at 34 in Fig. 2 and this outlet is connected by a pipe 35 to an oil manifold 36 which has 95 several branches 37 extending to the bearings 14 above described. These branches 37 are detachably secured to the bearing members as by nuts 38 and thus the entire manifold is supported by the bearings. This 100 manifold and the pump may be mounted in place and connected together in the crank case with the lower part 11 removed and, of course, all of these parts except part of the pump, will be above the screen 18 when the 105 lower half of the crank case is in place. The pump itself, when the lower part 11 is positioned, will pass through the opening 25 in the screen 18 thus extending down into the lower part of the crank case a considerable 110

distance. The inlet of the pump 26 extends even farther down into the crank case, this inlet being shown particularly in Fig. 2 as formed in a casting 39 which is detachably secured as by the screws 40 to the lower part of the pump 26. This casting extends well down to the bottom of the crank case and has two vertical passages one of which, marked 41, is the inlet for the pump and the other of which, marked 42, is the passage for the overflow from the pump. This overflow passage is controlled by a spring pressed valve 43, the spring being shown at 44 and an adjusting screw for the spring being shown at 45. A port 46 permits the overflowing oil to pass back into the crank case. This valved overflow will, of course, limit the pressure of the oil in the outlet from the pump 26 and consequently limit the pressure in the oil manifold and the bearings.

The casting 39 above described forms a support for a screen 47 which is of substantially cylindrical shape, open at the top and closed at the bottom except for a finger opening 48. This screen slides on the support 39 and is held in place thereon by a cover 49 which is detachably connected to the lower part 11 of the crank case over the opening 24 by a series of bolts 50. This cover 49 is slightly depressed so that, together with the opening 24, it forms a well or depression in the lower part of the crank case so that the oil in the crank case will drain towards that point. The cover 49 may be removed and then the screen 47 may be removed for cleaning. With both the cover and screen off the adjusting screw 45 for the overflow valve may be turned for adjusting the spring.

Also supported on the casting 39 is a shield or guard 51 which is spaced from and surrounds the screen 47. This shield is also preferably cylindrical and its upper end is secured to a flange 52 formed on the support 39. Its lower end extends down into the depression formed by the cover 49 and the opening 24 and is slightly above the cover at this point so that all of the lubricant in the crank case, in passing to the inlet 41 of the pump inside of the screen 47, must pass under the shield 51. Thus there can be no very great collection of "sludge" or water in the bottom of the crank case because this heavier material would drain into the depression and pass under the shield 51 to the screen and thence, of course, to the inlet 41 of the pump. Thus any water or acid or other foreign substance that would pass through the screen 47 would be circulated through the bearings of the motor and distilled off. For instance, the oil which escapes from the bearings of the crank shaft is thrown up against the hot pistons and the cylinder walls and any water in the oil would be vaporized and would pass off

through the crank case vent. The same is true of sulphuric acid that is sometimes found in the oil, either originally or by reason of some of the engine fuel passing down around the pistons into the crank case.

It has been found that such collections of water and sulphuric acid in the crank case are very harmful to the steel parts therein, particularly the carbonized steel parts, and more especially when the motor has been standing for some time. The circulation of this material through the bearings, however, when the motor is hot, distills it off and frees the crank case of it. Thus the shield 51 is an important factor in preventing the collection of water and acid and keeping it in circulation through the system as long as there is any of it present.

It will be seen that, in addition to the removability of the screen 47, the support 39 is also removable through the opening 24.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

Having thus described my invention, what I claim and desire to secure by Letters Patent is:

1. In an internal combustion engine, the combination with upper and lower crank case parts, of a screen above the bottom of the lower crank case part and extending substantially across the crank case, said screen having an opening therethrough, an oil pump secured to the upper crank case part and extending through the opening in said screen when the lower crank case part is placed in position.

2. In an internal combustion engine, the combination with an upper crank case part, of a lower crank case part detachably secured to the upper part and forming an oil supply reservoir, a screen extending substantially across the crank case and secured in the lower crank case part above the bottom thereof, said screen having an opening therethrough, and an oil pump suspended from the upper crank case part and extending through said opening in the screen when the lower crank case part is placed in position.

3. In an internal combustion engine, the combination with the engine crank case, of an oil pump detachably secured to the crank case, a screen support detachably connected to the pump, and a screen slidably mounted on said support.

4. In an internal combustion engine, the combination with the engine crank case, of an oil pump mounted therein, a screen sup-

port detachably secured to the oil pump and comprising a conduit forming the inlet conduit of said pump and a screen on said support over said inlet conduit.

5. In an internal combustion engine, the combination with a pump, of a screen support detachably connected thereto, said support constituting an inlet and an overflow outlet for said pump, and a screen over said

10 inlet and outlet.

6. In an internal combustion engine, the combination with a pump having an inlet and an overflow outlet, of a screen surrounding and enclosing said inlet and outlet so

15 that the overflow oil may be drawn into the inlet without passing through the screen.

7. In an internal combustion engine, the combination with the crank case thereof, of a pump having an inlet in the crank case,

having a main outlet to bearings within 20 the crank case, and having an overflow outlet, and a screen surrounding and enclosing said inlet and said overflow outlet.

8. In an internal combustion engine, the combination with the crank case, of a screen 25 arranged in the crank case above the bottom thereof and extending substantially across the crank case, said screen having an opening therethrough, an oil pump mounted in the crank case and adapted to be extended 30 through said opening when the parts are assembled, and a flange on said oil pump adapted to substantially fill said opening when the pump is in operative position in

35 the crank case.

In testimony whereof I affix my signature.

JESSE G. VINCENT.
